UNITED STATES PATENT OFFICE.

HENRY E. HAYWARD, OF PHILADELPHIA, PENNSYLVANIA, ASSIGNOR TO LINK-BELT COMPANY, OF CHICAGO, ILLINOIS, A CORPORATION OF ILLINOIS.

DESIGN FOR A CHAIN.

42,436.

Specification for Design.

Patented Apr. 30, 1912.

Application filed December 9, 1911. Serial No. 664,881. Term of patent 14 years.

To all whom it may concern:

Be it known that I, HENRY E. HAYWARD, a citizen of the United States, residing in Philadelphia, Pennsylvania, have invented a certain new, original, and ornamental Design for a Chain, of which the following is a specification, reference being had to the accompanying drawing, forming part thereof.

Figure 1, is a plan view of a chain illus-

trating my design; and Fig. 2, is a side elevation of a chain illustrating my design.

I claim:—

The ornamental design for a chain, as shown.

HENRY E. HAYWARD.

Witnesses:

W.M. E. SHUPE,

W.M. A. BARR.
